(No Model.)

W. S. LAUMASTER.

SHIPPING CAN.

No. 286,831.

Patented Oct. 16, 1883.

UNITED STATES PATENT OFFICE.

WINFIELD S. LAUMASTER, OF PHILADELPHIA, PENNSYLVANIA.

SHIPPING-CAN.

SPECIFICATION forming part of Letters Patent No. 286,831, dated October 16, 1883.

Application filed May 3, 1883. (No model.)

To all whom it may concern:

Be it known that I, WINFIELD S. LAUMASTER, of Philadelphia, in the county of Philadelphia and State of Pennsylvania, have 5 invented a new and valuable Improvement in Shipping-Cans; and I do hereby declare that the following is a full, clear, and exact description of the construction and operation of the same, reference being had to the annexed 10 drawings, making a part of this specification, and to the letters and figures of reference marked thereon.

Figure 1 of the drawings is a vertical transverse section of my improved shipping-can. 15 Fig. 2 is an elevation, and Fig. 3 is a top view.

My invention has relation to incased cans for shipping oil, and has for its object to provide an inexpensive, strong, and durable can 20 with a casing easily removable, and which can be renewed with little expense and labor when damaged or worn out, and also to provide a top for a shipping-can having sufficient strength to withstand the wear and tear of transportation, and also to provide a means for closing 25 the opening in the top of the can hermetically, so that none of the oil can escape.

My invention accordingly consists of the 30 novel combination, construction, and arrangement of parts comprising a shipping-can, as hereinafter described and claimed.

In the drawings, A represents a can, of sheet metal or other desired material, having a convex cone-shaped breast, B, stamped or formed 35 in one piece, having corrugations b, for strengthening purposes, and a gutter, b', at the base of the plain or unthreaded nozzle C, which is soldered on or is a part of the same piece of metal of which the breast is formed. Said breast is 40 secured to the body A of the can by a flange-joint, a.

D represents the wooden or other casing, composed of one or more strips or staves, d d, held together by two or more hoops, E E', the 45 former being the upper and the latter the lower hoop, respectively. The wooden bottom D is secured to the staves d by the nails e e, which pass through said hoop E and staves into said bottom, thereby forming a very strong 50 and durable bottom and attachment therefor for said casing.

To the upper hoop, E, or to the upper part of the casing, preferably the former, if the latter is of wood, are secured cleats or lugs F F, which are bent over the top edge of the casing and soldered or otherwise fastened to the breast B or flange a, (represented at f f,) thereby firmly and durably uniting the casing to the can, with the upper edge of the casing abutting against the flange. To separate said 60 parts, the lugs or cleats F F are cut, or their soldered ends are loosened by applying heat thereto, whereupon the can is lifted out of the casing.

G represents a smooth or unthreaded stopple 65 countersunk on the inside, the countersunk part slightly projecting down on the inside of the nozzle, and the stopple fitting on the outside of the nozzle, and having an exterior flange, g, which rests within the gutter b', 70 which is designed to be filled with any suitable cement, (indicated at g'), so as to hermetically seal the can. The latter is designed to be provided with the usual bail or handle, if desired. I have shown the nozzle and stopple 75 being unthreaded; but, if desired, they may have a screw-joint in addition to the cement seal.

What I claim is—

1. A shipping-can for oils, &c., having a 80 convex cone-shaped breast with corrugations terminating adjacent to a centrally-located gutter, from which projects a nozzle, substantially as shown and described.

2. A shipping-can for oils, &c., having a 85 convex cone-shaped breast, a nozzle, and a gutter at the base of said nozzle, substantially as shown and described.

3. A shipping-can for oils, &c., having a 90 convex cone-shaped breast, a nozzle, and a gutter at the base of the latter, combined with a stopple having a flange fitting on said gutter, and a cement joint therefor, substantially as shown and described.

In testimony that I claim the above I have 95 hereunto subscribed my name in the presence of two witnesses.

WINFIELD S. LAUMASTER.

Witnesses:

MATT CLIFTON,

GEORGE W. SELTZER.
